UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

TELEGRAPHIC TRANSMITTING-KEY.

No. 824,031.

Specification of Letters Patent.

Patented June 19, 1906.

Application filed February 11, 1905. Serial No. 245,221.

To all whom it may concern:

Be it known that I, ISIDOR KITSEE, of the city and county of Philadelphia and State of Pennsylvania, have invented certain new and useful Improvements in Telegraphic Transmitting-Keys, (Case No. 236,) of which the following is a specification.

My invention relates to an improvement in telegraphic transmitting-keys, and has for its object to produce a key whereby current-reversals may readily be transmitted.

Referring to the drawings, Figure 1 is a plan view of the device embodying my invention with the electrical connections shown in diagram. Fig. 2 is a side elevation of the same. Fig. 3 is a plan view of my invention in a modified form.

A is the key lever or tongue secured to the stationary part *a* with the interposition of the spring *A* in a manner so as to be movable horizontally. This lever is provided with the contacts *a'* and *a''*, respectively, both of these contacts being in electrical connection with each other and the lever.

B and *B'* are two springs supported and held in position by the two binding-posts *b* and *b'*, respectively, these springs being normally in contact with the two contacts *C* and *C'*, respectively.

D and *D'* are two adjustable contacts.

The spring *B* is provided with the contact *a'*, and the spring *B'* with the contact *a''*.

The lever *A* is connected to the line of transmission *F* either directly or with the interpolation of the necessary devices. This lever *A* occupies a central position, as is illustrated in Figs. 1 and 3.

The binding-posts *D* and *D'* are each connected with source of current, here shown as the batteries 1 and 2, the binding-post *D* connected through wire *E* with the negative pole of battery 1, the positive pole of which is grounded at *Z*, the binding-post *D'* connected through wire *E'* with the positive pole of the battery 2, the negative pole of which is grounded at *Z*. The contact *C* is connected with wire *G*, grounded at *Z*. The contact *C'* is through wire *H* electrically connected with the spring *B*, and the spring *B'* is electrically connected with the lever *A*.

Normally—that is, when the key is not in use—the lever *A* occupies a central position,

as stated above, and is only connected with the transmitting-line *F* and through the spring *B'*, contact *C'*, wire *H*, spring *B*, contact *C*, wire *G* to the ground *Z*. The contacts *D* and *D'* are normally out of connection with any part of the key, excepting the batteries 1 and 2, respectively.

This key is more specially designed to transmit impulses of opposite direction or, in other words, to transmit true reversals, as is outlined in Letters Patent No. 777,259, granted to me under date of December 13, 1904, for a system of telegraphy, wherein true reversals are used, a transmitted impulse of one polarity always being followed by an impulse of opposite polarity. In some cases—as, for instance, in submarine telegraphy—it is of great advantage that as soon as an impulse is sent over the cable the terminal of the same should be grounded at once. The reason for this is well understood by persons versed in the art, and it suffices to say here that the discharging of the condensers connected to the cable, as well as the cable itself, is facilitated through this ground, and I have provided in this transmitting-key the automatic grounding through the intermediate contacts *C* and *C'* and the springs *B* and *B'*.

The operation of this key is as follows: The operator in transmitting impulses over the line moves the key-lever to the right or left, as the case may be. It is supposed that he first wishes to transmit a positive impulse. He therefore in accordance with the arrangement as illustrated in Fig. 1 has to move the lever to the left, and in the course of this movement the contact *a'* on the lever *A* connects with the contact *a''* on the spring *B'* and pushes this contact away from the contact *C'* and in connection with the contact *D'*. As soon as through the movement of this lever the connection of *B'* and *C'* is broken the ground connection of the line is also broken, and when in its further movement the point *a'* connects through the point *a''* with the contact *D'* the connection of the line with the battery 2 is made, and an electrical impulse flows in the direction of the arrow from battery 2, through wire *E'*, point *D'*, *a''*, *a'*, *A*, *A'*, *a*, *F*, and (as the line of transmission is grounded on the other terminal) back to the ground *Z*. As soon as the operator releases

the lever A the same will assume its central or normal position, and the pressure on the spring B' being removed the same will break its connection with the contact V' and will connect with the contact C', thereby effectually grounding the line of transmission F. The movement of the lever A to the right has the same effect as the movement of the lever to the left, with the exception that now an impulse flows over the line of a polarity opposite to the polarity of the former impulse. The lever in moving toward the right first connects its point a² with the point a³ of the spring B, moves this spring B out of contact with the point C, and moves the point a³ toward and in contact with the point D. Through the breaking of the contact between C and spring B the ground connection of the line F is broken, and through the contact of a² and a³ and D the connection of the line F with the battery 1 is established, which connection allows a current to flow from the positive pole toward the ground Z, and (as the line of transmission is grounded on the other terminal) through said line, lever A, contact a², contact a³, D, wire E, back to the battery 1. The releasing of the lever A will again break the connection between it and the contacts a³ and D, whereby the flow of the battery will cease, and the spring B released of its pressure will again contact with C, thereby again effectually grounding the line F.

In Fig. 3 I have omitted the automatic grounding device, and this key is best adapted for such lines where the capacity is not great enough to necessitate the grounding of both terminals after each transmitted impulse. In this figure similar letters indicate similar parts.

The movement of the lever A to the right sends a negative impulse over the line and the movement of the lever to the left sends a positive impulse over the line. In its normal position—that is, when not in use—the lever does not connect with any of the batteries.

I have illustrated in Figs. 1 and 3 the source of electric current as to consist of two batteries each grounded; but it is obvious that instead of two batteries one large battery may be used grounded in the center or middle, which in reality is the equivalent of a battery split in two.

Having now described my invention, what I claim as new, and desire to secure by Letters Patent, is—

1. In combination with a line of transmission, a transmitting-key embracing a main lever connected to said line, a contact-lever on each side of said main lever connected each through stationary contacts with the ground, stationary contacts connected to sources of current and means whereby through the movement of the main lever, the line is connected to one or the other of said sources.

2. A transmitting-key embracing a support, a main lever, means to connect said main lever to an outside circuit, said main lever provided with contacting points on each side, a contact-lever on each side of said main lever, a stationary contact for each of said contact-levers, one of said stationary contacts connected with one of said contact-levers, the second of said stationary contacts provided with means to connect the same to an outside circuit, the second of said contact-levers connected to the main lever, a binding-post on each side of said movable levers, each of said binding-posts provided with means to connect the same to an outside circuit.

3. In combination with a line of transmission, a transmitting-key provided with means to connect said line, when in normal position, to the ground and provided with means to break said ground and connect said line with one pole of a source of current if moved to the right and with an opposite pole of a source of current if moved to the left.

4. A telegraphic transmitting-key provided with a movable lever, stationary contacts, and movable conductors interposed between said lever and said contacts, said movable conductors normally in electrical contact with each other, and with the movable lever, and adapted to be brought out of contact with each other through the movement of said lever.

In testimony whereof I hereby sign my name, in the presence of two subscribing witnesses, this 9th day of February, A. D. 1905.

ISIDOR KITSEE.
